J. C. CHRISTENSEN

REFRIGERATOR

Filed March 31, 1926

Jens C. Christensen
INVENTOR
By *J. W. Lewis*
ATTORNEY

UNITED STATES PATENT OFFICE.

JENS C. CHRISTENSEN, OF BUFFALO, NEW YORK.

REFRIGERATOR.

Application filed March 31, 1926. Serial No. 98,910.

My invention relates in general to refrigerators and more particularly to a refrigerating body for ice cream trucks.

It is well known to those skilled in the art, 5 that in ice cream trucks where brine is used as the refrigerant, the brine penetrates the woodwork of the body and comes to the outer painted surface thereof, with the result that the brine partly or wholly destroys the paint 10 thereon. Furthermore, due to the difference in temperature between the body and the outside atmosphere, there will be a "sweating" 15 or a condensing of the humidity of the air upon the surface of the present day ice cream truck body, which also deteriorates the paint on the outside surface of the same.

It has been an object of my invention to provide a body in which it shall be practically impossible for the brine to reach and 20 penetrate the outside wall and surface thereof.

Another object has been to provide a device whereby "sweating" upon the outside surface of the body shall be prevented.

25 Furthermore, by means of my device, I get a lower temperature than has been heretofore possible in this type of refrigerator, and I am able to retain this temperature for a greater length of time.

30 The objects above pointed out have been accomplished by the device shown in the accompanying drawing. In the drawing, the single figure is a perspective view of my invention, with portions broken away and sectioned.

My device comprises an inner refrigerating compartment 5, formed by two inner side walls 6 and a floor 7. The brine tank 8 of 40 the device is preferably supported on top of the side walls 6 and may be constructed in any of the well known ways. In the form shown, the tank is provided with a plurality of longitudinal partitions 9, with cross partitions 10 in each of which are formed perforations 11. It is preferable that the partitions do not extend clear to the top of the pan. By this means and by means of the apertures 11, the surging of the brine and ice, due to the motion of the truck, is retarded.

50 Surrounding each of the inner walls 6 and each of the side walls of the brine tank is a cork wall 12. It is preferable to provide insulating paper on each side of this cork wall as is customary. An outer cork wall 13 is provided and is arranged in interspaced rela-

tion with the cork wall 12. A plurality of nailing strips 14 are arranged between the cork walls 12 and 13 and these form spaces 20 between the walls. The cork walls 13 are also preferably faced with insulating paper. A 60 plurality of nailing strips 15 are provided on the outside of the cork wall 13, and to these nailing strips is secured each of the outer side walls 16 of the body. The nailing strips 15 serve to keep the wall 16 of the body in interspaced relation with each of the outer cork walls 13. The nailing strips 15 are in staggered relation with the nailing strips 14 as shown in the drawing, so that at no point in the body is there a solid thickness of wall 70 which is not broken by one or more air spaces. It is this structure which prevents the brine from penetrating through the walls of the body and reaching the outer surface of the outer walls 16. A top 17 is provided for the 75 body, which preferably has a cork lining 18. Insulating paper may also be placed on each side of this lining. The top extends over to and joins the side walls 16 so that the spaces 19 between the outer cork walls 13 and the outer walls 16 are closed at the top. The spaces 19 are open only at their bottoms.

By this provision, the air in the spaces 19 will be kept at such a temperature that "sweating" of the walls 16 will be prevented, 85 but no circulation of air, which is sufficient to raise the temperature of the refrigerating compartment 5 any appreciable degree, will be possible. By leaving the bottom of the spaces 19 open, any condensation which 90 occurs on the outside of the outer cork walls 13 will be free to run to the bottoms of the spaces 19 and drip from the lower edges of the walls 13 without coming in contact with the outer walls 16, thus preventing any accumulation of condensation in the spaces 19. The spaces 20 between the outer cork walls 13 and the cork walls 12 are closed at their tops by the top 17 of the body and at the bottom by the subfloor 21 of the body. The spaces 19 are also closed at their tops by the top 17. A cork lining 22 is placed between the subfloor and the floor 7 of the refrigerator compartment.

Obviously, some modifications of the details herein shown and described may be made without departing from the spirit of my invention, or the scope of the appended claims, and I do not, therefore, wish to be limited to the exact embodiment herein contained.

Having thus described my invention what I claim is:

1. A refrigerator comprising inner refrigerator walls, an inner cork side wall in contact with the inner refrigerator wall at each side of the refrigerator, an outer cork wall in spaced relation with each of the inner cork walls, and an outer side wall in spaced relation with each of the outer cork walls, the spaces between the inner and outer cork walls being closed and separated from the spaces between the outer cork walls and the outer side walls, the spaces between the outer walls and the outer cork walls being separate and non-communicating and open only at the bottom, whereby both sides of the outer walls will be subjected to atmospheric temperature.

2. A refrigerator comprising a top, a subfloor, an inner refrigerator side wall at each side of the refrigerator, an inner cork side wall in contact with each inner side wall, an outer cork side wall in spaced relation with each inner cork wall, the inner and outer cork side walls extending from the top to the subfloor, thus forming sealed air spaces therebetween, and an outer side wall in spaced relation with each outer cork wall, each of the outer side walls extending from the top to a point substantially opposite the outer edge of the subfloor, whereby the space formed between each outer side wall and each outer cork wall is open only at the bottom for the admission of atmospheric air.

3. A refrigerator comprising a top, a subfloor, an inner refrigerator side wall at each side of the refrigerator, an inner cork side wall in contact with each inner side wall, an

outer cork side wall in spaced relation with each inner cork wall, the inner and outer cork side walls extending from the top to the subfloor, thus forming sealed air spaces therebetween, and an outer side wall in spaced relation with each outer cork wall, the space between the outer side wall and the outer cork wall at each side of the refrigerator being separate and non-communicating, each of the outer side walls extending from the top to a point substantially opposite the outer edge of the subfloor, whereby the space formed between each outer side wall and each outer cork wall is open only at the bottom for the admission of atmospheric air.

4. A refrigerator comprising a top, a subfloor, an inner refrigerator side wall at each side of the refrigerator, an inner cork side wall in contact with each inner side wall, an outer cork side wall in spaced relation with each inner cork wall, the inner and outer cork side walls extending from the top to the subfloor, thus forming sealed air spaces therebetween, an outer side wall in spaced relation with each outer cork wall, each of the outer side walls extending from the top to a point substantially opposite the outer edge of the subfloor, and a plurality of nailing strips arranged in the spaces between the inner and outer cork walls and the outer cork wall and the side wall, the strips in the adjacent spaces being in staggered relation, whereby the outer side walls are insulated from the inner cork walls and subjected to atmospheric temperature.

In testimony whereof, I have hereunto signed my name.

JENS C. CHRISTENSEN.
